[57] **CLAIM**

The ornamental design for a combined carrier and hanger for fireman's gear, as shown.

DESCRIPTION

FIG. 1 is a side elevational view of a combined carrier and hanger for fireman's gear showing one embodiment of my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view of a second embodiment of my new design; and

FIG. 7 is a front elevational view of this second embodiment.

FIG. 1

FIG. 2

FIG. 3

FIG. 4

FIG. 5

FIG. 6

FIG. 7
